ELECTRIC CIRCUIT BREAKER
OPERATING MECHANISM

Frank H. Murphy, West Hartford, Conn., assignor to
General Electric Company, a corporation of New
York

Original application June 3, 1964, Ser. No. 372,193, now
Patent No. 3,265,833, dated Aug. 9, 1966. Divided
and this application Oct. 21, 1965, Ser. No. 510,113
3 Claims. (Cl. 200—116)

This is a division of application Ser. No. 372,193, filed
June 3, 1964, now Patent No. 3,265,833, granted Aug. 9,
1966.

My invention relates to electric circuit breakers, and
more particularly to multi-pole electric circuit breakers
of high current capacity type including separable
contacts operated by quick-make, quick-break type operating
mechanism, which breakers are capable of interrupting
"short-circuit" valve currents as well as intermediate valve
"overload" currents.

It is a general object of the present invention to pro-
vide a multi-pole electric circuit breaker of the molded
insulating case type having an electrical current carrying
and short-circuit current interrupting rating substantially
double that of comparable prior art circuit breakers of
comparable size. More particularly, it is a general object
of the invention to provide an electric circuit breaker
having a current carrying rating of 225 amperes at 240
volts, the external dimensions of which are not appre-
ciably greater than the dimensions of the most directly
comparable prior art circuit breaker having a rating of
100 amperes at 240 volts.

Two basic problems are encountered in attempting to
increase the electrical current rating of circuit protective
devices of the short-circuit interrupting type. These are
(1) to increase the size of the current carrying elements
of the device, and especially of the contact members, so
as to be able to carry the substantially increased current
without excessive heating, and (2) to provide in the lim-
ited space, an operating mechanism of sufficient strength
to furnish substantially increased contact pressure under
normal conditions and to be able to move the larger con-
tact members to open position fast enough to interrupt
the higher overload and short-circuit currents.

In accordance with the invention an operating mecha-
nism is provided of the cam-and-roller type as disclosed
in copending application Ser. No. 241,304, filed Nov. 30,
1962, now Patent No. 3,171,922, issued Mar. 2, 1965,
and assigned to the same assignee as the present invention,
in which the lower toggle links supporting the roller
comprise portions of a single U-shaped member having
opposed parallel sides which serve to support the pivot
pin carrying the operating roller, whereby any possible
misalignment or movement of the two side portions dur-
ing use is substantially prevented.

In the drawings,

FIGURE 1 is an elevational sectional view of an electric
circuit breaker incorporating the invention, taken substan-
tially along the line 1—1 of FIGURE 2, the supporting
side plate of the operating mechanism nearest the viewer
being omitted to show the parts better;

FIGURE 2 is a plan view of a three-pole electric circuit
breaker incorporating the invention, a portion of the cas-
ing cover being broken away;

FIGURE 3 is a side elevation view of the operating

2

mechanism of the circuit breaker of FIGURE 1, the parts
being shown in the "off" condition;

FIGURE 4 is a perspective view of a portion of the
operating mechanism of the circuit breaker of FIGURE
1, and

FIGURE 5 is a fragmentary elevational view of por-
tions of the circuit breaker of FIGURE 1, showing par-
ticularly the mounting of the mechanism in the casing.

Referring to the drawings, the invention is shown in

FIGURES 1 and 2 as incorporated in a three-pole electric
circuit breaker including a generally rectangular insulat-
ing casing comprising a base 10 and a cover 11. The
base 10 includes opposed integral side wall portions 12
(only one shown) and intermediate partition portions 13
(only one shown) defining three elongated generally
rectangular recesses or pole chambers 14 (only two
shown). The cover includes corresponding side and par-
tition portions 12 and 13 of the base respectively to sub-
stantially total enclose the pole chambers 14. (The side
portions of the cover 11 are not shown, and only one par-
tition portion 13' is shown, see FIGURE 1.) The cover
11 is attached to the base 10 by suitable means such as
by screws 11'.

Each of the pole chambers 14 has a stationary contact
15, supported on a line terminal conductor or strap 16.
Each of the line terminal straps 16 is fastened to the
base 10 by suitable means such as by pairs of screws 17,
and carries a line connecting lug 18 attached thereto by
suitable means, not shown. Each of the line lugs 18 is
of the screw clamp type and includes a clamping screw 19.

The opposite end of the base 10 includes a load ter-
minal conductor or strap 20 for each pole chamber, also at-
tached to the base 10 by suitable means such as by pairs
of screws 21, and support load connecting lugs 22 each
including clamping screws 23.

Each of the load straps 20 has a heater conductor 24,
including a U-shaped portion passing around a magnetic
field piece 25, and having its inner end connected to a
pair of flexible conductors 26 by means of a screw 27',
which also serves to fixedly attach this end of the con-
ductor 24 to the base 10.

The other end of each of the flexible conductors 26 is
rigidly attached by suitable means, such as by brazing, to
movable contact members 27. The movable contact
members 27 are each pivotally carried by a generally
U-shaped contact carrier 28 by means of an inverted
U-shaped clamp 29 and a pivot pin 30. (Note: One side
of the U-shaped carrier is broken.) Each of the movable
contact members 27 includes a contacting surface portion
27' disposed and arranged to engage a corresponding sta-
tionary contact 15. A compression spring 31 is disposed
between the bight portion of each of the contact carriers
28 and an end portion of the corresponding movable con-
tact member 27 to provide contact pressure when the
mechanism is in the closed circuit position as indicated
in FIGURE 1. A stop pin 32 is carried by the contact
carrier member at the opposite side of the movable con-
tact member 27 from the compression spring 31, to serve

as a stop to limit rotation of the contact carrier member
27 under the influence of spring 31 when the parts are
in the open circuit position as indicated for example in
FIGURE 3.

The current path through each of the poles of the cir-
cuit breaker may therefore be traced as follows: current
enters at line terminal 18, flows through line terminal strap
16 to stationary contact 15, to movable contact surface

27', to movable contact member 27, to flexible conductor 26, to heater conductor 24, to load terminal strap 20, to load lug 22.

The contact carrier 28 for the central pole of the circuit breaker, as illustrated in FIGURE 1, is pivotally supported by a fixed pivot pin 33, which in turn is supported by a pair of mechanism side plates 34. The contact carriers 28 of each of the three poles are ganged together for simultaneous operation by a contact cross-arm 35 which is generally square in cross-section, and comprises a metallic core member 35A and a generally rectangular insulating sheath 35B. Each of the contact carriers 28 is rigidly attached to the cross-arm 35 by suitable means such as by means of a generally U-shaped clamping member 36.

For the purpose of aiding in the extinction of an arc drawn between the movable contact surface 27' and the stationary contact 15, an arc extinguisher assembly is provided comprising a pair of side plates 38 of insulating fiber and a back wall 38' also of insulating fiber. A plurality of spaced ferro-magnetic metallic plates 39 are supported in spaced parallel relation between the arc chute side plates 38. Each of the plates 39 is generally U-shaped and the aligned openings of the plates 39 define a passageway through which the outer end portion of the movable contact member 27 moves in going from closed to open circuit position. An arc drawn between the contact members 27' and 15 is therefore drawn into the magnetic plates 39, and the arc gasses are vented through a screen member 40.

Operating mechanism

For the purpose of moving the center contact carrier 28, and with it the two outside contact carriers 28, with a quick-make and quick-break action, an operating mechanism is provided, which will not be described. The operating mechanism not only serves to move the movable contact members 27 between open and closed circuit positions, but also moves the contact members from closed circuit to open circuit position upon the occurrence of predetermined overload and/or short-circuit conditions in the circuit, and indicates such a "tripped" condition by movement of the operating handle to a trip signalling position. In addition to the side plates 34, the mounting and operation of which will be described later, the operating mechanism includes a handle assembly comprising a handle member 41 which is supported on a manually operable member 42 of metallic material, pivotally supported on a pair of projections 43 carried by and projecting outwardly of the side plates 34 of the mechanism. The operating mechanism also includes a releasable cam member 44, which is pivotally supported on a fixed pivot pin 45 extending between the side plates 34. The releasable cam member 44 includes a curved cam surface or edge portion 46, for a purpose to be described, and a latched end portion 47.

The releasable cam member 44 is normally restrained from rotation in a counterclockwise direction as viewed in FIGURE 1 by means of a restraining latch 48 carried by a common trip bar 49 extending across all three poles of the breaker, and pivotally supported at its opposite ends by suitable means such as by pivot pins 50 journaled in corresponding recesses in the side walls of the casing of the base 10. The common trip bar 49 is adapted to be rotated, so as to cause release of the latch member 48, by the action of current responsive means associated with any of the three poles of the circuit breaker and comprising for each pole an elongated bimetallic strip 51 rigidly attached to the heater conductor 24 at one end by suitable means such as by welding or brazing. Each of the bimetallic strips 51 carries an adjusting or calibrating screw 52. Each of the bimetallic strips 51 is disposed and arranged so that when heated by the heater conductor 24, it warps so as to move the calibrating screw 52 to the left as viewed in FIGURE 1, rotating the trip bar in counterclockwise direction to release the latch 48. Magnetic cur-

rent responsive means is also provided for each pole of the circuit breaker comprising a pivotally supported armature member 53 pivotally supported by lugs 53A extending sideways into corresponding pivot recesses 54 in opposed confronting portions of the side walls 12 and partitions 13 of the base 10. Each of the armatures 53 includes extension portions or legs 53B which are disposed and arranged to be attracted by the end portions of magnetic field piece 25 upon the passage of predetermined currents through the conductor 24. Attraction of the legs 53 toward the field piece 25 causes counterclockwise rotation of the armature 53 and causes its upper end to engage the trip bar 49, rotating it in counterclockwise direction to cause tripping as previously described. A light biasing spring 55 is provided for biasing each of the armatures 53 in clockwise direction, each of the springs 55 extending between a lug portion 53C of the corresponding armature 53 and the lower edge portion of the magnetic field piece 25. Certain aspects of the thermal-magnetic trip construction disclosed herein are the subject of a separate application Ser. No. 359,567, Jencks and Murphy, assigned to the same assignee as the present invention.

The central contact carrier member 28 has a generally U-shaped operating yoke 57 which is pivotally connected thereto by pivot pin 30 which also pivotally supports the movable contact member 27 on the contact carrier 28, the pin 30 passing through aligned holes 57A in the yoke member 57, see FIGURE 4. The upper ends of the legs of the yoke member 57 carry a cam roller supporting pin 58, which in turn supports a cam roller 59 and one end of each of a pair of tension type operating springs 60. Because of the use of a single integral member comprising the U-shaped member 57, there is substantially no danger of the pin 58 swinging about an axis perpendicular to its axis of rotation such as might occur if the two side portions 57B and 57C were separate link members as in the aforementioned application Ser. No. 241,304.

The cam roller 59 includes a pair of opposed flange portions 59A which facilitate travel of the cam roller 59 along the cam surface 46 of the releasable cam member 44. The upper ends of the tension type operating springs 60 are supported by the bight portion of generally U-shaped manually operable member 42 by suitable means, such as by having a loop portion thereof extending through slots in the manually operable member and being trapped against movement therethrough by retaining pins 61.

In operation, when the parts are in the closed circuit position as shown in FIGURE 1, the tension type operating springs, acting between the pivot pin 58 and the bight portion of the manually operable member 42, tend to cause movement of the cam roller 59 toward the left as viewed in FIGURE 1 because the center of curvature of the cam surface 46 lies to the right of the line of action of the spring in this position. Movement of the cam roller 59 and its pivot pin 58 to the position shown in FIGURE 1 forces the contact carrier member in counterclockwise direction, bringing the movable contact surface 27' of the movable contact member 27 into engagement with the stationary contact 15. As this occurs, the contact member 27 is rotated slightly clockwise about its pivotal support 30 on the contact carrier 28, compressing the contact pressure spring 31.

Movement of the handle member to the right as viewed in FIGURE 1, moves the upper ends of the springs 60 to the right, this movement continues until the line of action of the springs passes to the right of the center of curvature of the cam surface 46. When this occurs, the operating springs 60 move the cam roller 59 to the right, moving the contact carrier 28 and the associated movable contact members 27 clockwise about the pivotal support 33. Movement of the central contact carrier 28 in clockwise direction is limited by engagement of the pin 30 carried by the central contact carrier 28 with edge portions of the side plates 34 forming a corner. See particularly FIGURE 5. This movement takes place with

a snap action, independent of the rate of movement of the handle 41.

When the parts are in the closed circuit position as shown in FIGURE 1, an overload or short circuit condition which causes rotation of the trip bar 49 as described above causes release of the releasable member 44 from the latch 48. When this occurs, the force of the operating springs 60 pulling upward on the cam roller pin 58 urging the cam roller 59 against the cam surface 46, causes counterclockwise rotation of the releasable member 44 about its pivotal support 45. This permits movement of the cam roller 59 upwardly and slightly to the right even though the handle member 41 is held in the "on" position, and so permits automatic opening of the contact members.

As illustrated in FIGURES 1 and 5, and particularly in FIGURE 5, the mechanism side plates 34 each include a first leg portion 62, which rests against the back wall 10A of the base 10. The side plates 34 are also supported at the opposite end by means of a cross pin 63 which extends through the side plates 34 and has its end portions resting in notches 64 in the inner sides of the partitions 13 of the base 10. It will be observed that the side plates 34 merely rest against the base 10 at the support points 62 and 63. The plates 34 are drawn toward the back wall 10A of the base 10 by means of screws 65 which thread into alternately offset portions 66 of the plates 34. The screw 65 pulls the intermediate portion 67 of the side plates 34 toward the back wall 10A.

As shown in FIGURE 5, the side plates 34, and particularly the depending portions 62 and 67, are dimensioned so that the pin 63 engages the notch 64 and the leg 62 engages the back wall 10A of the casing 10 before the lower edge of the intermediate portion 67 can engage the back wall 10A of the casing. Thus, when the screw 65 is in fully tightened condition as shown in FIGURE 5, a small space 68 exists between the lower edge of the projection 67 and the back wall 10A of the casing base 10. Thus only a single fastening element is used for each side frame 34. It will also be observed that by means of the mounting structure shown, the side frames 34 are supported both at the extreme front and extreme rear portion, that is, at the opposite ends thereof, thereby providing a very secure mounting, although the space used at the back wall of the casing 10 for the mounting is relatively small. It will be observed that the pin 63 which rests in the notches 64 extends substantially directly over the stationary contact 15. Thus the forward part of this pole chamber is used for two purposes. (1) to house a portion of the arc extinguisher structure including the stationary contact, and (2) to contain and support a portion of the operating mechanism. Since the supporting point of the pin 63 is at the upper edge of the base portion 10, it is sufficiently removed from the supporting point of the stationary contact 15 and the stationary contact supporting strap 16 to prevent the possibility of a dielectric oversurface failure between these two points which danger would exist if this end of the frame were supported adjacent the back wall of the casing.

The handle support member 42 is bifurcated at its lower end to fit over the supporting pivot pin 43. In addition, the handle member 42 includes enlarged portions 42A adjacent the lower end which serve the purpose of retaining the pin 30 in position when the parts are assembled in the center pole, thereby preventing the pin 30 in this pole from sliding lengthwise to a position where it might be struck by the edge of the handle support member 42. The corresponding pins 30 in the outside pole members are retained in place by the corresponding side wall 12 and partitions 13.

It will be observed that the entire mechanism assembly 70 is held in assembled relation without the need for any special retaining means holding any of the pivot pins in their position. Thus the pins 30 and 32 are retained in place, although free to slide lengthwise, by the adjacent partitions and side wall portions of the base. Also, since 75

the side portions 57B and 57C comprise integral parts of a single U-shaped member, no separate retaining means is required to retain these portions on the corresponding ends of the pin 58. In assembly, the pin 58 is snapped in between the side portions 57B and 57C by springing these parts apart slightly.

The entire circuit breaker therefore has its assembly greatly facilitated since virtually all of the parts may be assembled by hand and without any metal working operations such as riveting, welding, brazing, etc. to hold the parts together. In accordance with the invention, an extremely compact high spring force mechanism is provided. Thus for example, the contact pressure of the most nearly similar prior art circuit breaker of this size is about 5 pounds, whereas in the construction in accordance with applicant's invention, the contact pressure achieved is from 8 to 10 pounds.

While the invention has been disclosed in only one particular embodiment, it will be readily appreciated that numerous modifications thereof may readily be made. It is therefore intended by the appended claims to cover all such modifications as fall within the true spirit and scope of the invention.

What I claim as new and desire to secure by Letters Patent of the United States is:

1. An electric circuit breaker comprising:
  - (a) a support;
  - (b) at least one pair of relatively movable contacts;
  - (c) means supporting said relatively movable contacts on said support;
  - (d) contact operating means supported on said support for operating said relatively movable contacts between open and closed circuit positions;
  - (e) said contact operating means including a cam member having an arcuate cam surface;
  - (f) means pivotally supporting said cam member on said support;
  - (g) latch means supported on said support and releasably engaging said cam member and normally restraining said cam member in a first position;
  - (h) a manually operable member;
  - (i) means supporting said manually operable member on said support for reciprocal movement between open and closed circuit positions;
  - (j) said contact operating means also including an elongated contact arm and means supporting said contact arm on said support for reciprocal movement between open and closed circuit positions respectively;
  - (k) a generally U-shaped member having a bight portion and a pair of opposed side portions terminating in free end portions and means rigidly connecting each of said side portions to said bight portion and preventing substantial independent movement of said side portions;
  - (l) means pivotally connecting said U-shaped member to said contact arm for pivotal movement about an axis extending adjacent and generally parallel to the bight portion of said U;
  - (m) a cam follower roller;
  - (n) means supporting said cam follower roller on said U-shaped member for rotation about an axis extending between said free end portions of said side portions and substantially parallel to said bight portion of said U;
  - (o) said cam follower roller being in engagement with said cam surface of said cam member and moving reciprocally along said cam surface between first and second positions corresponding to said open and closed circuit positions of said contact arm;
  - (p) spring means interconnecting said cam follower roller and said manually operable member, said spring means acting on said cam follower roller to urge said cam follower roller into engagement with said cam surface.

2. An electric circuit breaker as set forth in claim 1, wherein said cam member is positioned between said contact arm and said manually operable member and said movement of said manually operable member between said open and closed circuit moves said spring means across the center of curvature of said arcuate cam surface.

3. An electric circuit breaker as set forth in claim 1, wherein said U-shaped member comprises a unitary elongated metallic member.
